Edward P. Alexander

ATTORNEY

UNITED STATES PATENT OFFICE.

LAYTON M. PARKHURST, OF INDIANAPOLIS, INDIANA, ASSIGNOR TO GEORGE B. PITTS,
TRUSTEE, OF CLEVELAND, OHIO.

VENDING MACHINE.

Original application filed March 31, 1908, Serial No. 424,304, renewed July 23, 1915, Serial No. 41,617.

Divided and this application filed April 11, 1921, Serial No. 460,593.

This invention relates to improvements in vending machines, more particularly to machines for vending postage stamps, tickets and the like.

5 This application is a division of my application Serial No. 424,304, filed March 31, 1908, and renewed on or about the 23rd day of July, 1915, Serial No. 41,617.

10 One object of the invention is to provide a vending machine having but few parts of simple construction, compactly arranged and correlated to operate in a positive manner.

15 Another object of the invention is to provide in an apparatus of this character a mechanism for vending postage stamps, tickets and the like in which the controlling and operating elements are so correlated to permit but one operation upon the insertion 20 of a plurality of coins of a predetermined number.

25 A further object of the invention is to provide a mechanism of this character in which the controlling and operating elements are correlated to receive a plurality of coins but permit actuation of the mechanism only by the use of a predetermined number of coins for each vending operation or actuation of the delivery mechanism.

30 Other objects of the invention will be apparent to those skilled in the art from the following description taken in connection with the accompanying drawings, in which—

35 Figure 1 is a front view of a casing containing a plurality of vending units each embodying my invention.

Fig. 2 is a longitudinal sectional view on the line 2—2 of Fig. 1.

40 Fig. 3 is a fragmentary detail view.

Fig. 4 is a fragmentary elevation of certain of the elements for moving the set of coins past the arresting device.

Fig. 5 is a section on the line 5—5 of 45 Fig. 3.

In the drawings 1 indicates as an entirely a suitable housing or casing adapted to receive one or more combined stamp vending and money collecting units 2, 2, three such 50 units being illustrated in the drawings. The units or sections 2 are arranged side by side and may be removed therefrom independently of each other. Each unit comprises a box 14 that is divided into an up-

per and lower compartment by means of a 55 slide or platform 21 supported by inwardly turned ribs 22 on the side walls of the box. The lower compartment serves as a cash box. The upper compartment is subdivided by a vertically disposed partition 23, 60 preferably mounted on the platform 21. Upon one side of this partition is arranged the vending or stamp feeding mechanism (not shown), arranged to deliver the stamps or tickets through the opening 100 (see Fig. 65 1), being guided therefrom by the fingers 50' of the deflecting plate 50. Upon the other side of the partition 23 is arranged the coin controlled mechanism for actuating the stamp feeding mechanism. The coin 70 controlled mechanism comprises a locking cam 52, the periphery of which has a plurality of identically similar cam surfaces 53, equal in number to the number of stamp sections on the stamp cylinder (not shown), 75 one of the elements of the vending mechanism, and correspondingly positioned relative to the axis of the shaft 32. This cam wheel 52 is fitted, in any suitable manner, to the shaft 32 to turn therewith. At the 80 bottom of each of the recesses 53 is a notch 54 adapted to receive the free end of a locking dog 55 on a release rod 56. This release rod 56 is pivotally connected at its lower end to the partition 23, as indicated at 56'. 57 85 is a spring secured at 57' to the partition 23 and having its free end bearing against the release rod 56 and normally pressing its end carrying the dog 55 toward the locking cam 52. 90

58 is a ratchet drive wheel suitably secured to the shaft 32 to turn therewith. Its periphery is studded with a plurality of teeth 59, equal in number to the number of locking recesses 54 on the locking cam 52, 95 and each tooth 59 arranged to correspond with one of the said locking recesses on the locking cam.

60 is a bearing and guide bracket secured at 61 to partition 23 and having a bearing 100 opening at 62 for the shaft 32 and a vertically disposed guideway at 63. 64 is a main operating rod having its upper end fitted to and guided by the guide 63 on the bracket arm 60, and its lower end extending through a hole 21' in the platform or division plate 21. This operating rod carries a laterally projecting arm 65, prefer-

ably bifurcated to receive the lower end of a driving pawl 66, the upper end of which is toothed at 66' to engage with the teeth 59 on the ratchet 58, one after the other. 5 The driving pawl 66 is pivotally connected at 66^a to the arms 65. 67 is a spring secured at 67' to the rod 64 and having its upper end normally pressing outwardly on the lower end 66^b of the oscillatable pawl 66, so as to 10 normally press the tooth 66' toward the ratchet wheel 58. The innermost section 65' of the lateral arm 65 on the main operating rod 64 carries a slide 68 arranged to bear at its inner edge against the partition 15 23 and to keep the upper end of the rod 64 suitably spaced from the ratchet wheel 58. 69 and 70 are lateral extensions carried by the rod 64, each of them being preferably bifurcated to receive the reduced end 20 of one of the oscillatable links 71, 72, each of which is pivoted to one of said extensions. Each of these links 71, 72, has its upper end reduced in thickness, as indicated at 71', 72', and fitted to oscillate in a slot 25 in one of the slotted arms 73, 74, carried by the main operating rod 64. 75 is a coil spring preferably surrounding the rod 64 between the lateral projections 69, 70 thereon and the division plate 21, and tending to 30 normally press the rod 64 upwardly, as indicated in Fig. 2. 76 is a plate, grooved as indicated at 77, to form with the partition 23 a coin passageway 78, the upper end of which terminates in a coin-receiving slot 99, and the lower end of which registers 35 with a coin-discharge slot 79 in the division plate 21. 80 and 81 are slots formed in the plate 76 and each adapted to receive one of the pins or projections 82, 83 which 40 extend inwardly from the links 71, 72, respectively. The upper ends of the slots 80, 81, extend through the plate 76 to points outside of or beyond the opposite end walls of the coin slot 77 so that when the rod 64 is in normal position at the end of its movement upwardly under the influence of the spring 75, the pins 82 and 83 will be disposed to opposite sides of and beyond the 45 path of movement of the coins through the slot 77, thus permitting the coins, when inserted, to fall or move to a position in the slot 77 below the pins 82, 83, as will later be described. These slots 80 and 81 are so shaped that, as the main operating rod 64 50 is depressed, the walls of the slots first guide the pins 82, 83 on the links 71, 72, toward the longitudinal axis of the rod 64, thereby simultaneously drawing together the upper ends of the links, as shown in Fig. 3, and 55 then vertically downward, tending to maintain the links 71, 72 with their upper ends adjacent to the rod 64 and with the pins 82, 83 in the coin passageway 77. 84 is a coin-actuated element adapted to throw the release rod 56 and the locking pawl 55 thereon, 60

away from the locking cam 52. I prefer to have this release rod-actuating element 84 and anti-friction roller. This roller 84 has an axial aperture 84'. 85 is a pin extending through the aperture 84' into the metal of the partition 23 and the coin guide plate 70 76 at either side of the roller. The metal of the coin guide is recessed at 86 to permit the roller 84 to be projected through the recess 86 and have its periphery engage with the front wall of the release bar 56. The diameter of the pin 85 is considerably less than the diameter of the aperture 84' through the anti-friction roller 84, so as to permit lateral motion of the roller relative 75 to the said pin, while at the same time retaining the roller in the recess 86. As shown, the operating rod 64 is engaged at its upper end by a thrust rod 90, which in turn is pivotally connected to a lever 88^a which 80 is pivoted at 88' to a bracket 87 supported by the housing 14. 85

In my present construction, the dog 55 is arranged to be operated by a plurality of 90 coins of a predetermined number or set and the devices 82, 83 are so correlated with respect to the arresting device 84 that a set of coins may be inserted in the coin slot and properly disposed and correlated therein, whereby such set of coins may be moved past the arrester to cause a single actuation of the vending mechanism. As shown, the coin slot is of sufficient width to permit the passage 95 of the coins edgewise, so that when a set of coins is inserted the first coin will engage and be arrested by the arresting device 84 and the succeeding coins of the set will engage therewith and with one another, edge to edge, in the coin slot ready for actuation 100 by the pins 82, 83. 105

In the drawings I have shown a mechanism in which the controlling and operating elements are correlated to actuate the vending mechanism when a set of two coins is inserted in the coin slot and arrested by the device 84. As will be understood from Fig. 3, if a set of coins is inserted in the slot the first coin will be arrested by the device 84 and the second coin will engage with the edge of the first coin and be arrested thereby; if the operating handle 88^a is then operated, it will move the rod 64 endwise, carrying with it the pins 82, 83, which being guided by the slots 80, 81, will move inwardly and engage the uppermost coin (second coin in this instance). As the downward movement of the pins continues, they will force both coins past the arresting device 84 and thus release the dog 55 from the cam 52. 115 120 125

To those skilled in the art of making mechanism of the class described, many alterations in construction and widely differing embodiments and applications of my invention will suggest themselves, without de- 130

parting from the spirit and scope thereof. My disclosures and the description herein are purely illustrative and are not intended to be in any sense limiting.

5 What I claim is:

A vending machine comprising article delivery mechanism, a casing having a coin box in its lower part and a coin chute in its upper portion with a slot opening into said chute, said chute being of a length to receive a plurality of coins and of a width substantially equal to that of the coins to maintain the coins in edgewise contact, a laterally movable stop means projecting into said

chute to engage beneath the lowermost coin, locking means for the article delivery mechanism arranged to be released on movement of said stop means when the coins are pushed past the latter, and means normally resting out of the chute and above the uppermost coin of said plurality of coins but adapted on movement to initially enter the chute above the uppermost coin and to subsequently move downwardly substantially to said stop means whereby in one stroke, to push 25 the plurality of coins past said stop means.

In testimony whereof I affix my signature.

LAYTON M. PARKHURST.
